**BREAK-AWAY OPERATOR FOR SELF-
RESTORING SWITCH**

Stanley E. Anderson, Niles, Ill., assignor to Illinois Tool Works, Chicago, Ill., a corporation of Illinois
Filed Sept. 10, 1959, Ser. No. 839,134
4 Claims. (Cl. 200—61.41)

This invention relates to switch-operating structures, and more particularly relates to structures for causing both operation and restoration of an electrical switch to occur responsive to each forward operation of a forward-and-return switch operator.

The principal object is to provide a switch operator on the noted character including parts which, following switch operation, are arranged to break away from each other on a continuation of the forward movement, thereby permitting restoration of the operated switch while the switch operator remains in forward position. Thereby, the operated time of the switch is limited to the interval elapsing between arrival of the switch operator in its switch-operating position and its arrival in its break-away position, and is independent of the dwell-time of the operator in positions forward of its switch-operating position and is also independent of the return time of the operator.

A common form of switch generally comprises a spring contact member arranged to be operated by a switch operator such as a lever or plunger. A minimum amount of pressure on the lever causes the spring member to be thrown into its operated position to close and/or open a set of contacts at a required amount of pressure. The switch remains operated, until the operating pressure is relieved, at which time it returns automatically to its unoperated condition. Such devices have a wide variety of uses and particularly have been widely adopted for use in systems wherein a series of objects each requires control operation to be performed. In such systems arrangements each object in turn operates the switch ever to control or energize the circuit whereby the control operation is performed. As the control operation must often be kept from extending over an undue period of time, it is necessary that the switch contacts be closed only momentarily.

In one example, a series of bottles or other objects carried by a conveyor arrangement or belt each in turn operates a switch lever to operate the switch contacts. The contacts in turn control a circuit for energizing a solenoid, to cause print or other markings to be registered on each bottle. As the location of each bottle on the conveyor may vary with respect to switch lever, control of the time with precision during which the lever is operated is difficult to achieve. If the switch contacts are closed for an unnecessarily long period of time during the passage of a bottle past the switch lever, the solenoid is likewise kept energized to operate the print platen or stamp to be applied to the bottle for a corresponding period. This results in poor print registration or smudged printing.

The present invention eliminates the problem of holding the switch contacts operated for an excess period of time by providing a two part switch operator or lever having one part pivotally mounted on the other and held in fixed relationship thereto by a predetermined force. The force is created by the field of a magnet mounted between the two parts. When first operated by one of the moving objects, the lever functions as one unit due to said force to close the switch contacts. After a sufficient movement is achieved to close the switch contacts the other part of the lever is held stationary. If the pressure on the other part continues and exceeds the predetermined force, that part is left free to pivot or

2

travel under pressure of the object moving past it. With the held part of the lever released from the moving part of the lever, the held part immediately returns to its non-operated position under pressure of the spring contact member and the switch contacts are controlled accordingly. Thereby, only a momentary closing of the switch contacts results, which in turn insures that a print platen or stamp is held only momentarily against the object upon which the print is to be registered and prevents print smudging. When the object has moved past the one part, that part is freely attracted back to its unoperated position by the magnetic field.

It is, therefore, an object of this invention to provide a switch operating structure, which is adapted to enable the switch contacts to be operated for only a determinable time period.

It is also an object of the present invention to provide a switch operating structure whose travel is controlled independently of the object moving it, after it has reached a predetermined position.

It is a feature of this invention to provide a switch operating structure comprising two separable portions, one of which is operated by the other to operate a set of contacts whereafter they separate to permit return of the switch to its unoperated condition.

It is another feature of this invention to provide a switch operating structure having one portion thereof pivotally secured to a switch housing and the other portion pivotally secured to the first portion and held in a predetermined relationship to said first portion until a particular force is applied thereto.

It is still another feature of this invention to provide a switch actuator of two portions having a magnet therebetween for holding one portion in predetermined relationship to the other until the force applied to the one portion exceeds a particular value.

Other objects and features of this invention will become apparent with further reading of the specification and claims in conjunction with the drawings.

FIG. 1 of the drawings shows one arrangement of a switch 1 mounted for use in a conveyor system;

FIG. 2 is a section of the switch actuator arrangement taken along the line 2—2 in FIG. 1;

FIG. 3 is a view taken along the line 3—3 of FIG. 2;

FIG. 4 is a top plan view of the switch actuator arrangement; and

FIG. 5 is a diagram of the respective actuator positions.

Referring to FIG. 1, it will be seen that the switch assembly 1 is mounted on a bracket 2 adjacent a conveyor indicated at 6. Bottles 7 or other objects are carried by the conveyor 6 past the switch lever 3. It will be understood that instead of the cited example in which print is to be registered on the bottles, that other functions such as various machine operations may be desired to be controlled responsive to the movement of particular objects past the switch lever 3.

As seen in FIG. 2, the switch lever 3 is pivotally mounted between sides 5 on the lever arm 6 by means of pin 4 and bracket 19. Bracket 19 is provided with a protrusion 25, whose purpose will be explained. Adhering to the lever arm 6 is a small permanent magnet 8, which is partially surrounded by sides 5 of arm 6 to provide an excellent magnetic circuit therefor. Magnet 8 in turn holds lever 3 adjacent arm 6 so that arm 6 and lever 3 act as a unit.

Arm 6 is pivotally mounted by means of pin 10 between the brackets 11 on the switch 12. The elongated portion 13 of arm 6 forming one leg of a U therewith passes underneath pin 10 and extends above the switch plunger 14 for operating it.

The plunger 14, when operated, controls the spring

members 15 and 16 in any well known manner to open contacts 17 and close contacts 18. Spring members 15 and 16 are provided as illustrative of any well known snap-action switch arrangement; however, many other types of switch arrangements may be used with the invention. Contacts 17 and 18 each control respective circuits in any well known manner, and although two contacts are shown herein the number may be varied. The controlled circuits may, for example, be for energizing a solenoid and/or other electrical device, which in turn may control, for example, a pneumatic or hydraulic valve for controlling the operation of a print platen, roll or stamp, all in any well known manner to perform a corresponding operation.

When a bottle 7 is traveling past the lever 3, it transmits its movement through lever 3, magnet 8, and arm 6. The magnet 8 and arm 6 follow the movement of lever 3 by pivoting as one unit about pin 10. Portion 13, therefore, also rotates to depress or operate the plunger 14. The plunger 14 operates the snap-action switch members 15 and 16 to close contacts 18 and energize a solenoid, for example, for an already described purpose. Shortly thereafter, protrusion 25 on bracket 19 encounters the housing of switch 12.

In FIG. 5, it will be seen that the arm 6 and lever 3 in being operated, travels from the position indicated by line 21 to the position indicated by line 22. With the snap-action switch 14 operated, and protrusion 25 held against the switch housing, further movement of the plunger 16 and lever arm 6 is restrained. Alternatively, the movement may be restrained by the back pressure of the spring contact members. The bottle 7, if still exerting force on the lever 3, therefore, causes the separation of lever 3 from lever arm 6, on exceeding the attractive force of the magnet 8. The lever 3 then freely pivots about pin 4 under the force of the moving bottle 7 to a position such as shown by line 23 in FIG. 5, after which the bottle 7 loses contact with switch lever 3. Bracket 19 also prevents the movement of arm 3 beyond the position indicated by line 23 so that it is held within the magnet field of magnet 8.

In the meantime, the lever arm 6 returns to its unoperated position due to the force of spring members 15 and 16 exerted on plunger 14, as it is free from the pressure of the moving bottle. Thus the switch is only momentarily operated to control the solenoid accordingly. The momentary energization of the solenoid results in only the momentary operation of the printing apparatus so that the print is properly registered.

Thereafter, as the bottle 7 continues to travel, it travels past the lever 3. With the force of the moving bottle removed from lever 3, the magnetic field exerted by magnet 8 is sufficient to attract the lever 3 and return it to its unoperated position adjacent arm 6 so that the operation may be repeated for the next bottle or object passing the switch lever 3.

Thus having described one embodiment of my invention, I am appending hereto a series of claims which I believe to incorporate the inventive concept.

I claim:

- 5 1. For use with a switch having a spring member for controlling contacts, the improvement comprising a lever arm arranged to operate said spring member to control said contacts, a second lever arm, means for retaining the second lever arms in predetermined relationship to said first lever arm whereby an object moving said second lever arm moves said first lever arm to operate said spring member and contacts whereafter said second lever arm is released from said first lever arm to permit said spring member and contacts to be returned to their unoperated condition while said second lever arm is still operated by said object, said second lever arm being pivotally mounted on said first lever arm, said first lever arm being pivotally mounted on said switch.
- 10 15. 2. Control means for a switch structure of the type wherein a self-restoring switch is mounted on a supporting structure which also supports a switch-operating member mounted for a reciprocable movement between a normal position and a switch-operated position, the control means comprising a driving lever and a driven lever mounted with the supporting structure of the switch for a forward and a return movement between normal and forward positions, the driven lever being disposed directly behind the driving lever, clutch means interposed
- 20 25 between the driving and driven levers for causing forward movement of the driving lever to drive the driven lever forwardly to operate the switch through its said operating member, forward-driving lever movement in excess of switch-operating requirements releasing the clutch means to free the driven lever for an immediate return movement which permits the said switch and its operating member to return to normal position with the driving lever still in forward position, subsequent return of the driving lever to normal position causing the clutch means to reengage.
- 25 30 3. Control means according to claim 2, wherein at least one of said levers is magnetic, the said clutch comprising a permanent magnet attached to the other lever and normally engaging said one lever.
- 35 40 4. Control means according to claim 2, wherein the said driven lever is pivotally secured to the said supporting structure of the switch, and the said driving lever is pivotally secured to the driven lever.
